CLAIM

The ornamental design for a golf glove as shown and described.

DESCRIPTION

FIG. 1 is a Perspective view of a golf glove showing my new design;

FIG. 2 is a Top view thereof;

FIG. 3 is a Bottom view thereof;

FIG. 4 is a Front view thereof;

FIG. 5 is a Back view thereof;

FIG. 6 is a Left-side view thereof;

FIG. 7 is a Right-side view thereof; and,

FIG. 8 is a Perspective view of a golf glove showing in use view.

The broken lines in the drawings depict portions of the golf glove that form no part of the claimed design.

1 Claim, 8 Drawing Sheets
